(57) **CLAIM**

The ornamental design for a child seat for automobile, as shown and described.

DESCRIPTION

FIG. 1 is a perspective view of the child seat for automobile.

FIG. 2 is a front elevational view of FIG. 1.

FIG. 3 is a rear elevational view of FIG. 1.

FIG. 4 is a left side elevational view of FIG. 1.

FIG. 5 is a right side elevational view of FIG. 1.

FIG. 6 is a top plan view of FIG. 1.

FIG. 7 is a bottom plan view of FIG. 1; and,

FIG. 8 is a perspective view of the child seat for automobile shown in use.

The broken lines in the drawings depict portions of the child seat for automobile that form no part of the claimed design.
